US0D1033937S

(12) **United States Design Patent** (10) **Patent No.:** **US D1,033,937 S**
(45) **Date of Patent:** **** Jul. 9, 2024**

(54) **CHAIR**

(71) Applicant: **Grand Rapids Chair Company**, Byron Center, MI (US)

(72) Inventors: **Timothy Stoepker**, Grand Rapids, MI (US); **Sarah Gesink**, Byron Center, MI (US)

(73) Assignee: **Grand Rapids Chair Company**, Byron Center, MI (US)

(**) Term: **15 Years**

(21) Appl. No.: **29/813,418**

(22) Filed: **Oct. 28, 2021**

(51) LOC (14) Cl. **06-01**

(52) U.S. Cl.

USPC **D6/334**; D6/336; D6/379

(58) **Field of Classification Search**

USPC D6/334, 335, 336, 374, 376, 379

CPC A47C 5/04

See application file for complete search history.

(57) **CLAIM**

The ornamental design for the chair, substantially as shown and described.

DESCRIPTION

FIG. 1 is a perspective view of a chair, according to a first embodiment of the present invention;

FIG. 2 is a front elevation view of the chair of FIG. 1;

FIG. 3 is a rear elevation view of the chair of FIG. 1;

FIG. 4 is a right-side elevation view of the chair of FIG. 1;

FIG. 5 is a left-side elevation view of the chair of FIG. 1;

FIG. 6 is a top plan view of the chair of FIG. 1;

FIG. 7 is a bottom plan view of the chair of FIG. 1;

FIG. 8 is a perspective view of a chair, according to a second embodiment of the present invention;

FIG. 9 is a front elevation view of the chair of FIG. 8;

FIG. 10 is a rear elevation view of the chair of FIG. 8;

FIG. 11 is a right-side elevation view of the chair of FIG. 8;

FIG. 12 is a left-side elevation view of the chair of FIG. 8;

FIG. 13 is a top plan view of the chair of FIG. 8; and,

FIG. 14 is a bottom plan view of the chair of FIG. 8.

The broken lines shown are included for the purpose of illustrating environment of the design and form no part of the claimed design.
